[57] CLAIM

The ornamental design for driving lever for a labelling apparatus, as shown.

DESCRIPTION

FIG. 1 is a side elevational view of the driving lever for a labelling apparatus embodying my new design;

FIG. 2 is a cross-sectional view taken along line 2—2 in FIG. 1;

FIG. 3 is a cross-sectional view taken along line 3—3 in FIG. 1;

FIG. 4 is a top plan view thereof;

FIG. 5 is a front elevational view thereof; and

FIG. 6 is a perspective view taken from the rear of the driving lever for a labelling apparatus embodying my new design.
